ABSTRACT OF THE DISCLOSURE

The present invention relates to a fermentative process for obtaining the antibiotic, oxytetracycline, by means of a new species of Streptomyces, named by us *Streptomyces henus* or *Streptomyces* F.I. 1782, and which has been deposited at the Institute of Microbiology of the Rutgers University, U.S.A., where it received the index I.M. 3872. The process of the present invention results in obtaining oxytetracycline in very high yields. These yields are shown to be as high as 11,000 γ per cc.

10

Specification

Our invention relates to a fermentative process for obtaining the antibiotic, oxytetracycline, by means of a new species of Streptomyces, named by us *Streptomyces henus* or *Streptomyces* F.I. 1782, and which has been deposited at the Commonwealth Mycological Institute, Ferry Lane, Kew, Surrey, England, where it received the index number I.M.I. 109,532, and at the Institute of Microbiology of the Rutgers University, U.S.A. where it received the index I.M. 3872.

25

The antibiotic oxytetracycline, its preparation and its chemical, physical and biological properties, are widely

2

described in the literature (S. A. Waksman: "The Actinomycetes," vol. III, 1962, p. 329).

We have found that by the process of our present invention, oxytetracycline may be obtained with high yields.

This new microorganism has been isolated from a soil sample taken in the neighborhood of Ramera (Italy) and shows the following morphological, macroscopic, microscopic and biochemical properties:

Microscopic aspect

The vegetative mycelium on culture media of potato-agar and Czapek-agar consists of hyphae 0.8-0.9 μ thick, of intermediate length, branched and forming aerial mycelium consisting of hyphae from 1.2 to 1.6 μ thick and not very long. These hyphae abundantly ramify and form straight conidiophores bearing spiralled hyphae then transforming into spores.

The conidia have a smooth surface, are prevalently oval: 1.2 to 1.6 μ by 1.4 to 1.7 μ and are disposed first in chains and then free; each chain bearing more than ten spores. The hyphae transforming into spores are attached to conidiophores alternatively or oppositely. The spirals are closed, sometimes forming clews.

Macroscopic aspect

In Table I there are listed the cultural properties observed on the media therein indicated, in which the microorganism is grown at 28° C., observations being made at the 3rd 8th, 16th and 21st day after inoculation.

Biochemical properties

The microorganism reduces nitrates to nitrites, hydrolyzes starch and gelatin, does not produce hydrogen sulphide, does not coagulate or peptonize milk, and does not produce melanin and digest tyrosine. It produces acids from d-mannose, d-arabinose, glucose, mesoinosite, d-fructose, adonitol, maltose and rhamnose but not from d-xylose, sorbitol, or saccharose. The microorganism does not form sclerotia and does not grow at 50° C.

¹ According to the Pridham et al. classification, Appl. Microbiol., 1958, 6, p. 52.

Legend in Table II: + = Positive reaction; — = Negative reaction; ± = Very weak reaction.

Identification of the microorganism

The description of the microorganism under examination relates to the genus *Streptomyces* Waksman and Henrici (Bergey's Manual of Determinative Bacteriology, 7th ed., 1957, pp. 744-745). From examination of the species it may be concluded: In the classification system of Pridham et al. (Appl. Microbiol., 1958, 6, p. 52) the microorganism belongs to the section "Spira" series White; in the classification system of Baldacci (Giorn. Microbiol., 1958, 6, p. 10), the microorganism belongs to the series "Albidoflavus"; and in the classification system of Waksman (The Actinomycetes, vol. II, 1961, p. 123) the microorganism belongs to the series "Flavus."

A comparison between the properties of the microorganism *Streptomyces* F.I. 1782 and those of species belonging to the above systematic groups (Taxa) demonstrates that *Streptomyces* F.I. 1782 has quite different properties. Besides the differences listed in Table II, *Streptomyces* F.I. 1782 has a clearly different morphology from *Streptomyces rimosus*: The hyphae of the former transforming into spores are alternatively or oppositely attached along straight sporophores; while in the latter the hyphae forming spores are attached to short sporophores in a more or less compact fascicled system. Hereinbelow follows a list of the differences from species belonging to the cited Taxa group which do not produce tetracyclines.

Streptomyces F.I. 1782 differs from the species *S. flavus*, because generally the latter does not produce spirals, in the color of the vegetative and aerial mycelium, and because it does not reduce nitrates (Waksman S.A.: The Actinomycetes, vol. II, 1961, p. 210); from the species *S. flavovirens* because the latter generally does not produce spirals, forms soluble pigments, and coagulates or peptonizes milk (Waksman, The Actinomycetes, vol. II, 1961, p. 210); from the species *S. flavogriseus* because the latter does not produce spirals and forms a mouse-gray colored aerial mycelium (Waksman, The Actinomycetes, vol. II, 1961, p. 209); from the species *S. chrysomallus* because the latter does not form spirals and produces soluble pigments (Waksman, The Actinomycetes, vol. II, 1961, p. 193); from the species *S. celluloflavus* because the latter produces soluble pigments and presents a different color of the aerial mycelium (Waksman, The Actinomycetes, vol. II, 1961, p. 191); from the species *S. viridans* because the latter produces soluble pigments and presents a different color of the aerial mycelium (Waksman, The Actinomycetes, vol. II, 1961, p. 286); from the species *S. albidoflavus* because the latter produces soluble pigments and in the color of the aerial mycelium (Waksman, The Actinomycetes, vol. II, 1961, p. 168); from the species *S. citreus* because the latter shows a different color of the vegetative and aerial

mycelium (Waksman, The Actinomycetes, vol. II, p. 196); from the species *S. parvus* because the latter produces soluble pigments and shows a different color of the vegetative and the aerial mycelium (Waksman, The Actinomycetes, vol. II, 1961, p. 255); from the species *S. griseoflavus* because the latter shows a different color of the vegetative and the aerial mycelium, furthermore because it produces soluble pigments (Waksman, The Actinomycetes, vol. II, 1961, p. 222); from the species *S. flavochromogenes* because the latter produces soluble pigments and shows a different color of the vegetative and the aerial mycelium (Waksman, The Actinomycetes, vol. II, 1961, p. 209); from the species *S. alboflavus* because the latter does not form spirals and because it shows a different color of the vegetative mycelium (Waksman, The Actinomycetes, vol. II, 1961, p. 169); from the species *S. hygroscopicus* because the latter produces soluble pigments and shows a different color of the vegetative mycelium (Waksman, The Actinomycetes, vol. II, 1961, p. 230); from the species *S. fimicarius* because the latter produces soluble pigments and shows a different color of the vegetative and the aerial mycelium (Waksman, The Actinomycetes, vol. II, 1961, p. 208); from the species *S. abikoense* because the latter is melanin-positive, does not produce spirals and produces soluble pigments (Waksman, The Actinomycetes, vol. II, 1961, p. 165); from the species *S. alboniger* because the latter does not produce spirals and shows a different color of the aerial mycelium (Waksman, The Actinomycetes, vol. II, 1961, p. 170); from the species *S. hachijoensis* because the latter does not produce spirals and shows a different color of the aerial mycelium (Waksman, The Actinomycetes, vol. II, 1961, p. 226); from the species *S. eurocidicus* because the latter does not produce spirals and because it produces soluble pigments (Waksman, The Actinomycetes, vol. II, 1961, p. 205); from the species *S. mediocidicus* because the latter does not produce spirals, is melanin-positive and does not reduce nitrates (Waksman, The Actinomycetes, vol. II, 1961, p. 242); from the species *S. albidus*, v. *invertens* because the latter belongs to the species *S. griseus* (Waksman, The Actinomycetes, vol. II, 1961, p. 169); from the species *S. albus* because the latter produces a snow-white aerial mycelium peptonizes milk and shows different sporophores (Waksman, The Actinomycetes, vol. II, 1961, p. 172); from the species *S. cacaoi* because the latter produces long and open spirals, forms an aerial mycelium which is colored from light-gray to mouse-gray and reduces nitrates weakly (Waksman, The Actinomycetes, vol. II, 1961, p. 183); from the species *S. erythreus* because the latter produces a cream to purple-red aerial mycelium and wine-colored soluble pigments (Waksman, The Actinomycetes, vol. II, 1961, p. 204); from the species *S. gallieri* because the latter produces a cream-colored aerial mycelium, a brown

soluble pigment and liquefies gelatin weakly (Waksman, The Actinomycetes, vol. II, 1961, p. 215); from the species *S. longisporoflavus* because the latter produces long, open spirals, an aerial mycelium which is colored from white to lemon, coagulates and peptonizes milk, and hydrolyzes starch weakly (Waksman, The Actinomycetes, vol. II, 1961, p. 37).

It follows therefore that *Streptomyces* F.I. 1782 should be considered a species different from those known up to the present and therefore a new species which we have named *Streptomyces henetus*.

The microorganism *Streptomyces* F.I. 1782 may be stored by successive cultivation on a solid medium (potato-agar, Sabouraud agar) or by lyophilization, milk being the suspending medium.

The production of the antibiotic oxytetracycline according to the invention may be performed by cultivating *Streptomyces* F.I. 1782 in a liquid nutrient medium under aerobic conditions. A temperature of from 24° to 37° C., preferably 28° C., and a period of from 72 to 144 hours have been found satisfactory. The pH may vary from 6.1-6.5 to 8 according to the fermentative media employed.

The cultural medium should consist of a carbon source, a nitrogen source, and salts. The carbon source may be, for example, saccharose, glucose, dextrin, starch, soybean meal, peanut meal, cotton-seed meal, corn steep liquor, distiller's solubles, soyabean oil, or lard oil. The nitrogen source, besides the above complex substances containing nitrogen, may be meat extract, peptone, casein, hydrolysate of casein and ammonium salts, such as ammonium sulphate or diammonium phosphate. The mineral salts useful for the production of the antibiotic vary according to the medium employed. Calcium carbonate is normally present, and sodium, potassium, manganese, iron, copper, cobalt or zinc chlorides, sulphates or phosphates may be added. The fermentation may be carried out in Erlenmeyer flasks and in laboratory or industrial fermenters of various capacity.

The quantity of antibiotic present in the broth may be qualitatively assessed by paper chromatography in comparison with a standard sample of oxytetracycline and quantitatively checked by spectrophotometric or biological methods.

The yields obtainable by the process of the invention are as high as 11,000 γ per cc.

When the fermentation is over, the pH of the culture broth is adjusted to 2-2.5, the mycelium is separated by filtration or centrifugation, and the oxytetracycline may be recovered from the liquid phase and purified. Useful methods of purification are: extraction with an organic solvent, for example butanol, pentanol, hexanol, amyl alcohol, methyl ethyl ketone, methyl isobutyl ketone or butyl acetate; adsorption on a solid substance, for example activated charcoal, and subsequent elution with water or an organic solvent; precipitation of the antibiotic in the form of one of its derivatives or complex salts by means, for example, of an amine, a quaternary ammonium compound in the presence of a metal ion, ammonia or sodium carbonate, urea, N,N¹-malonylurea, sulphonated derivatives or sulphates. Oxytetracycline thus obtained may be then purified by recrystallization or transformed into its salts with a mineral or organic acid, such as hydrochloric, sulphuric, citric or tartaric acid.

The present invention includes a method of extraction and purification of the oxytetracycline produced, which comprises extracting the acidified culture broth, filtering the product and treating the resulting filtrate with oxalic acid, filtering, making alkali, extracting with a mixture of tricresol and carbon tetrachloride, separating the organic phase, treating it with aqueous hydrochloric acid and acetone and separating the aqueous phase. In a preferred embodiment, the culture broth is acidified with a mineral acid, for example hydrochloric, sulphuric or phosphoric acid, to pH 2-2.5, is filtered and the filtrate obtained is

first treated with oxalic acid and then filtered to remove precipitated calcium oxalate; the filtrate is extracted with a mixture of tricresol and carbon tetrachloride adjusting the pH to 8-8.5 by addition of alkali. The tricresol employed is that generally known and employed for industrial uses, having a specific gravity 1.030-1.038, consisting of a mixture of the three isomeric cresols. It is preferable to employ a mixture of tricresol and carbontetrachloride in a ratio 2:1 to 1:2 by volume. The phases thus obtained are separated by centrifuging and to the separated organic phase, which contains the antibiotic, a mixture of equal volumes of acetone and aqueous hydrochloric acid, preferably 1 N hydrochloric acid, is added. From the aqueous phase thus obtained and adjusted to pH 7, by addition of an alkaline material such as an alkali metal hydroxide or carbonate, the antibiotic oxytetracycline precipitates and is isolated and purified by recrystallization or transformed into a salt with a mineral or organic acid.

The following examples illustrate the invention, without intent to limit it.

EXAMPLE 1

Into each of two 300 cc. Erlenmeyer flasks, 60 cc. of the following medium is poured:

	Percent
Dextrin	3
Calcium carbonate	0.4
Corn steep liquor	0.3
Casein	0.5
Ammonium sulphate	0.1
Potassium hydrogen phosphate (K ₂ HPO ₄)	0.01
Tap water, to 1000 cc.	

and sterilized by heating in an autoclave to 120° C. for 20 minutes. The pH after sterilization is 6.8-7.0. Each flask is inoculated with 1.5 cc. of a suspension of spores obtained by scraping off, into 5 cc. of distilled sterile water, the surface of a 20 days old slant of a culture of *Streptomyces* F.I. 1782 grown on the following solid medium: 200 g. of peeled potatoes are boiled for about 20 minutes in 500 cc. of water. The volume is brought to its original value and filtered through gauze. 2% of glucose and 2% of agar are added. The volume is brought to 1000 cc. and sterilized in an autoclave at 120° C. for 20 minutes. The pH of the medium is 6.8-7.0. The flasks are incubated at 28° C. for 24 hours on a rotary shaker with a stroke of 30 mm. at 220 r.p.m. 1 cc. of a culture thus grown is used to inoculate Erlenmeyer flasks of 300 cc. with 60 cc. of the following productive medium:

	Percent
Starch	3
Corn steep liquor	0.3
Calcium carbonate	0.4
Casein	0.5
Ammonium sulphate	0.1
Potassium hydrogen phosphate (K ₂ HPO ₄)	0.01
Tap water, to 1000 cc.	

The sterilization is carried out at 120° C. for 20 minutes. The pH after sterilization is 6.7-7.0. It is incubated at 28° C. under the conditions described above for the vegetative medium. 4000 γ per cc. of oxytetracycline is produced after 96 hours of fermentation.

EXAMPLE 2

The operation is as in Example 1, with the difference that the culture to be inoculated is 10 days old and is grown on the following medium:

	Percent
Peptone	0.8
Glucose	4
Difco agar	2
Tap water, to 1000 cc.	

7
sterilized in an autoclave at 120° C. for about 1 minute. The pH is 6.8-7.0. In addition the productive phase differs in the composition of the medium being as follows:

	Percent
Starch	8
Corn steep liquor	2.5
Calcium carbonate	1
Ammonium sulphate	1
Manganese sulphate	0.015
Cobalt nitrate	0.00075
Cotton seed meal	0.5
Lard oil	3
Tap water, to 1000 cc.	

sterilized in an autoclave at 120° C. for 20 minutes. The pH of the medium after sterilization is 6.5-6.8. It is incubated at 28° C. under the same shaking conditions as in Example 1. 8500 γ per cc. of oxytetracycline is obtained after 144 hours of fermentation.

EXAMPLE 3

Operation is as in Example 2 with the difference that the culture is 20 days old and the vegetative phase is carried out on the following liquid medium:

	Percent
Corn steep liquor	3.5
Calcium carbonate	1.8
Saccharose	0.5
Distilled water, to 1000 cc.	

sterilized in an autoclave at 120° C. for 20 minutes. The pH after sterilization is 6.2-6.3. Incubation is for 26 hours at 28° C. on a rotary shaker with a stroke of 60 mm. at 220 r.p.m. The productive phase is carried out in 300 cc. flasks with 35 cc. of the following productive medium.

	Percent
Starch	8
Corn steep liquor	2.6
Calcium carbonate	1
Ammonium sulphate	1
Manganese sulphate	0.014
Cobalt chloride	0.00078
Cotton seed meal	0.43
1 cc. of lard oil for each flask containing 35 cc. of the medium.	

The pH after sterilization is 6.5-6.7. The medium is sterilized in an autoclave at 120° C. for 20 minutes. The quantity of the vegetative medium to be inoculated into the productive medium is 4.3% of the latter. The incubation of the productive phase is carried out for 24 hours at 28° C. and then at 24° C. for 120 hours. 7600 γ per cc. of oxytetracycline are obtained.

EXAMPLE 4

Operation is as in Example 2 with the difference that operation is always at 24° C. The production obtained in 96 hours of fermentation is 6400 γ per cc. of oxytetracycline.

EXAMPLE 5

Two 300 cc. Erlenmeyer flasks containing 60 cc. of the liquid medium in Example 1 are inoculated with a 20 days old culture of *Streptomyces* F.I. 1782, grown on the medium in Example 2. The medium is incubated at 28° C. for 24 hours under the conditions in Example 1. 20 cc. of the culture broth thus obtained are inoculated in 3000 cc. of the same liquid medium, contained in a 5 liter neutral glass fermentor provided with a screw-stirrer, an inlet tube for bubbling air under the screw-stirrer, a breakwater device, a tube for inoculation, air outlet tubes and a temperature checking equipment. Growth is carried out at 28° C. with an aeration rate of 3 liters per minute, and with shaking at a rate of 400 r.p.m. After 24 hours,

8
150 cc. of the culture broth thus grown are inoculated into 3 liters of the following productive medium:

	Percent
Fatless soyabean meal	3
Distiller's solubles	0.5
Glucose	2
Sodium chloride	0.25
Tap water, to 1000 cc.	

sterilized by heating in an autoclave at 120° C. for 20 minutes. The pH after sterilization is 6.5. The above medium is contained in a 5 liter neutral glass fermentor, having the above-described properties. During the fermentation, carried out at a stirring rate of 500 r.p.m. and with an aeration rate of 3 liters per minute, foaming is checked by adding small amounts of silicone antifoaming agent. The highest production of oxytetracycline obtained in 88 hours of fermentation corresponds to 5800 γ per cc.

EXAMPLE 6 (Purification)

The pH of 33.3 liters of a broth culture having an antibiotic concentration of 4500 γ per cc., obtained as described in any of the preceding examples, is adjusted to 2 by adding dilute 25% aqueous sulphuric acid. The culture broth is filtered with 1 kg. of infusorial earth and the filtration cake is washed with acidulated water (pH 2-sulphuric acid) so that the volume of the filtrate reaches 45 liters. 2.2 kg. of oxalic acid are added and the mixture is stirred for 30 minutes, filtered and the filter washed with water so that the volume of the filtrate reaches 50 liters. 50 liters of this broth filtered and decalcified, containing 150 g. of oxytetracycline and poured into a steel vessel, are shaken with a mixture of 2.5 liters of tricresol and 2.5 liters of carbon tetrachloride, the pH of the solution being adjusted to 8.3 with an aqueous solution of sodium hydroxide. The two layers making up the mixture are separated by centrifuging. The aqueous layer is extracted once again with a mixture of 1 liter of tricresol and 1 liter of carbon tetrachloride. The lower heavy organic layers are combined and poured into a mixture of 5 liters of acetone and 5 liters of aqueous 1 N hydrochloric acid and thoroughly shaken. The two layers are separated by centrifuging. The heavy layer is extracted twice again with 3 liters and 2 liters respectively of 1 N aqueous hydrochloric acid. The pH of the combined aqueous layers (10 liters) is adjusted to 7 by adding with stirring a dilute (20%) aqueous sodium hydroxide. A precipitate separates, which is recovered by filtration, washed with diethyl ether and dried in vacuo at 40° C. The residue is ground, washed again with ether and dried at 40° C. 150 g. of crude oxytetracycline are obtained.

150 g. of this product are suspended in 1.5 liters of methanol and dissolved by addition of 200 cc. of 13% hydrochloric acid in methanol. To the solution 14 g. of decolorizing carbon are added, it is stirred for 30 minutes, filtered on infusorial earth and washed with methanol. The filtrate is concentrated in vacuo to a volume of about 400 cc., and 30 cc. of 13% aqueous hydrochloric acid in methanol are added. On rubbing, a product crystallizes and the mixture is allowed to stand overnight at room temperature, filtered, washed first with 50 cc. of methanol and then with diethyl ether, and dried at 40° C. in vacuo. 95 g. of oxytetracycline hydrochloride are obtained.

EXAMPLE 7

65
Operation is as in Example 3, with the difference that the vegetative phase and productive phase are carried out at 27° C. and that the productive medium amount contained in each flask is 50 cc. A production of 11,000 γ per cc. of oxytetracycline is obtained after 6-7 days of fermentation.

We claim:

1. A process for preparing oxytetracycline, which comprises cultivating the new microorganism *Streptomyces henetus* Rutgers University Institute of Microbiology I.M.

3872 under aerobic conditions in a nutrient medium containing a source of carbon, nitrogen and mineral salts, at a temperature of from 24° to 37° C., over a period of from 72 to 144 hours, at pH 6.1 to 8, and separating the oxytetracycline thus formed from the fermentation broth and purifying the separated oxytetracycline.

2. A process for preparing oxytetracycline, which comprises cultivating the new microorganism *Streptomyces henetus* Rutgers University Institute of Microbiology I.M. 3872 under aerobic conditions in a nutrient medium containing a source of carbon, nitrogen and mineral salts, at a temperature of from 24° to 37° C., over a period of from 72 to 144 hours, at pH 6.1 to 8, acidifying the culture broth containing oxytetracycline to pH 2-2.5 with an inorganic acid, filtering and treating the filtrate with oxalic acid and filtering to remove calcium oxalate precipitated and making alkaline the filtrate obtained to pH 8-8.5 by adding an inorganic base and extracting with a mixture of tricresol and carbon tetrachloride, and transferring the oxytetracycline from the organic phase into an aqueous phase by a mixture of aqueous hydrochloric acid and acetone, and precipitating the oxytetracycline from the aqueous phase thus obtained by previous neutralization to pH 7, and purifying the oxytetracycline.

3. A process for preparing oxytetracycline, which comprises cultivating the new microorganism *Streptomyces henetus* Rutgers University Institute of Microbiology I.M. 3872 under aerobic conditions in a nutrient medium containing a source of carbon, nitrogen and mineral salts, at a temperature of from 24° to 37° C., over a period of from 72 to 144 hours, at pH 6.1 to 8, acidifying the culture broth containing oxytetracycline to pH 2-2.5 with an inorganic acid, filtering and treating the filtrate with oxalic acid and filtering to remove calcium oxalate precipitated and making alkaline the filtrate obtained to pH 8-8.5 by adding an inorganic base and extracting with a mixture of tricresol and carbon tetrachloride in a ratio of 2:1 to 1:2 by volume, and transferring the oxytetracycline from the organic phase into an aqueous phase by

a mixture of aqueous hydrochloric acid and acetone, and precipitating the oxytetracycline from the aqueous phase thus obtained by previous neutralization to pH 7, and purifying the oxytetracycline.

5 4. A process for preparing oxytetracycline, which comprises cultivating the new microorganism *Streptomyces henetus* Rutgers University Institute of Microbiology I.M. 3872 under aerobic conditions in a nutrient medium containing a source of carbon, nitrogen and mineral salts, at a temperature of from 24° to 37° C., over a period of from 72 to 144 hours, at pH 6.1 to 8, acidifying the culture broth containing oxytetracycline to pH 2-2.5 with an inorganic acid, filtering and treating the filtrate with oxalic acid and filtering to remove calcium oxalate precipitated and making alkaline the filtrate obtained to pH 8-8.5 by adding an inorganic base and extracting with a mixture of tricresol and carbon tetrachloride, and transferring the oxytetracycline from the organic phase into an aqueous phase by a mixture of aqueous 1 N hydrochloric acid and acetone in an equal ratio by volume, and precipitating the oxytetracycline from the aqueous phase thus obtained by previous neutralization to pH 7, and purifying the oxytetracycline.
